MIXING CHAMBER FOR SUCTION CLEANERS

Arthur M. McGuire, Philadelphia, Pa., assignor
to Hydroway, Incorporated, Philadelphia, Pa., a
corporation of Pennsylvania

Application February 10, 1949, Serial No. 75,648

10 Claims. (Cl. 183—19)

1
This invention relates to mixing chambers for suction cleaners and more particularly to such mixing chambers for mixing the entrained dust and dirt from a suction cleaner with water and then discharging the mixture to drain.

Heretofore I have proposed several different types of suction cleaners discharging the entrained dust and dirt into a water mixer for mixing the same with water and thereafter discharging the mixture to drain. Such suction cleaners are disclosed and claimed in my pending applications Serial No. 746,034, filed May 5, 1947; Serial No. 38,889, filed July 15, 1948; and Serial No. 96,610, filed June 1, 1949. All of these cleaners have been exceptionally efficient in that no bag of dust or dirt must be emptied by hand or need any tank of mixed water and dust or dirt be manually emptied. Further, my suction cleaners have the added advantage of discharging purified and humidified air from the mixing chamber into surrounding atmosphere. In my other cleaners the mixing chamber must be physically affixed to a water faucet or water tap and I have provided means for promptly and efficiently connecting the mixing chamber to the tap or faucet so that the same may be readily demountable. Such mixing chambers cannot be used with certain modern types of plumbing in which the discharge orifice for the water valves is built into the face of the sink or basin and merely discharges the water into the sink or basin in a generally downward and outward direction without using a nozzle type of faucet.

By the present invention I have provided a novel water mixer which can be used with all types of faucets and sinks or basins without the necessity of manually connecting the same to a water discharge orifice.

It is accordingly an object of the present invention to provide a novel water mixer for use with suction cleaners which can receive water from all types of faucet without the necessity of manually connecting the same thereto.

Another object is to provide such a mixer in which the entrained dust and dirt is efficiently mixed with the water and the mixture is thereafter discharged from the mixer to drain without spraying or splattering of water as it leaves the discharge orifices.

Another object is to provide such a mixer in which a minimum of air escapes through the water intake port so that water may flow readily therethrough.

Another object is to provide such a mixer in which the water in the bottom thereof cannot be

2
splashed upwardly therein to mix with the incoming entrained dust and dirt before the same is discharged into the water in the bottom of the mixer.

5 Another object is to provide such a mixer which is of simple construction and which may be readily dismounted and assembled by the users of my suction cleaner to clean the filters provided in the same.

10 Another object of the present invention is to provide such a mixer which can be readily and cheaply manufactured and which will be efficient in operation under all operating conditions.

Other and further objects of my invention will 15 appear from the following description thereof.

My novel mixer is capable of various mechanical embodiments one of which is shown in the accompanying drawings and is described herein-after for the purposes of illustrating the same.

20 This description of this illustrative embodiment of my invention should in no way be construed as defining or limiting the same and reference should be had to the appended claims for this purpose.

25 In the accompanying drawings, in which like reference characters indicate like parts,

Fig. 1 is a general view of a suction cleaner of the type which I have previously proposed showing the same in use with my novel mixer;

30 Fig. 2 is a cross sectional elevation of the novel mixer of Fig. 1; and

Fig. 3 is an expanded view of the novel mixer of Fig. 1 showing the several parts thereof in detail.

35 Referring now more particularly to Fig. 1, a suction cleaner is there shown comprising a cleaning head 10 connected by an expandable and contractible corrugated rubber hose 11 to the intake 12 of a horizontally disposed air pump 13 having an air impeller 14 driven by an electric motor 15 and provided with a discharge 16. Discharge 16 is connected by a second expandable and contractible corrugated rubber hose 17 to my novel

40 mixer shown generally at 18 and mounted within a sink or basin 19 provided with a drain 20 and a water tap 21. When motor 15 is energized fan 14 of air pump 13 creates a suction in inlet 12 and hose 11. When cleaning head 10 is moved

45 over a surface to be cleaned in the conventional manner dust and dirt from such surface is entrained in the air pulled through the cleaning head 10 and this air with entrained dust and dirt is discharged through discharge 16 into hose 17 and into mixer 18.

As will be seen in Figs. 2 and 3, mixer 18 com-

prises a lower cylindrical receptacle 22 which is provided with a bottom 23 and which is mounted upon suction cups 24 so that the same will be retained in position in sink 19. The upper end of receptacle 22 is open and is provided with an in-turned circumferentially disposed flange 25. A water intake 26 is provided adjacent the upper edge of receptacle 22 and is more or less semi-spherical in form and is open at its top 27 so that water discharged from any type of spigot can readily fall therethrough. A baffle 28 is provided within receptacle 22 behind intake 26 to prevent air from escaping therethrough. Air and water discharge vents 29 are let into the sides of receptacle 22 on both sides of intake 26 and extend through approximately three-quarters of the circumference of receptacle 22. Hand holds 30 are secured to the outside of receptacle 22 above vents 29 to provide a means for picking up and carrying the mixer 18. Hand holds 30 are so disposed with respect to vents 29 that any water and air discharged through vents 29 in an upward direction will impinge thereagainst and will be deflected downwardly thus preventing spattering of water through vents 29.

A cup-shaped vessel 31 provided with an out-turned circumferentially disposed upper flange 32 is mounted within receptacle 22 and extends downwardly so that the bottom 33 thereof is beneath the lowest point of intake 26. Circumferential flanges 32 and 25 may be suitably mated so that an air and water-tight seal is formed between them. Bottom 33 is centrally apertured at 34 to receive a downwardly extending tubular element 35 which terminates short of bottom 23. Bottom 33 is also provided with a plurality of the relatively small apertures 36. Vessel 31 is of reduced diameter at 37 to provide a circumferential shoulder 38 to receive filter housing 39.

Filter housing 39 is closed at its upper end 40 and is provided with a circular groove 41. End 40 is provided with a centrally disposed opening 42 to receive nipple 43 to which is suitably secured the corrugated expandable and collapsible rubber hose 17.

A cylindrical filter screen 44 is mounted in housing 39 and the open upper end 45 thereof fits snugly into groove 41. Filter 44 has a perforated filter bottom 45 and is spaced from the walls of housing 39. A spider 46 bears against bottom 45 and separates the same from gasket 47 mounted in housing 39. Gasket 47 is provided with a central aperture 48 and rests upon shoulder 38 of vessel 31. Gasket 47 is provided with a downwardly depending lip 49 surrounding aperture 48 for reasons that will appear hereinafter.

Vessel 31, housing 39 and receptacle 22 are secured together to form air-tight seals therebetween by any suitable means here shown as manually operable fasteners 50 pivotally mounted on housing 39 and engaging suitable indentations 51 in receptacle 22.

When the suction cleaner and the mixer of my invention are assembled as described with reference to Fig. 1 and when motor 15 is energized dust and dirt entrained with air flows through hose 17 into nipple 43, through opening 42 and into filter 44. Filter 44 collects large pieces of lint, cigarette butts and the like and the air with entrained fine particles of dust and dirt passes through the walls of filter 44 into the space between filter 44 and housing 39. The air with entrained fine particles of dust and dirt then passes downwardly around spider 46 through

opening 48 in gasket 47 into vessel 31. In the meantime the water has been turned on and faucet 21 discharges the same to fall freely into water intake 26 and a water level is built up in receptacle 22 the height of which depends upon the amount of air passing into the receptacle and approximates the water level shown at 52. In any event the water level is sufficiently high to cover end 33 and openings 34 and 36 of vessel 31. The air with entrained particles of dust and dirt passing through opening 48 enters the water within vessel 31 and passes downward primarily through tubular element 35 but also in lesser degree through openings 36. By providing openings 36 less turbulence is created at the discharge end of element 35 and the action of the air on the water in receptacle 22 is reduced so that excessive splashing does not take place. The water in vessel 31 and receptacle 22 separates the entrained particles of dust and dirt from the air and the air passes upwardly in receptacle 22 and outwardly through vents 29. Excess of water in receptacle 22 passes with the air through vents 29 so that the water level in chamber 22 is maintained relatively constant and the mixture of dust and dirt and water flows off through drain 20.

Baffle 28 is so disposed that air passing upwardly in receptacle 22 which is deflected downwardly from shoulder 38 and flange 25 will not disturb the water flowing into intake 26 and will permit the same to flow freely into receptacle 22. Downwardly depending flange 49 of gasket 47 is provided to minimize splashing of water upwardly from chamber 31 into housing 39 and will deflect splashed water from the undersurface thereof of back into vessel 31.

When filter 44 becomes filled with large particles of lint, paper, cigarette butts and the like it will usually suffice to detach nipple 43 and reverse housing 39 to pour the same to waste through opening 42. However, it may be necessary from time to time to clean filter 44 and under such circumstances it is a simple matter to remove gasket 47 and spider 46 from housing 39, and then withdraw filter 44 from groove 41 and housing 39 so that filter 44 may be readily and easily cleaned.

It should be particularly noted that in my novel mixer it is not necessary for the discharge opening of faucet 21 to be connected to intake 26 and the mixer operates in a most efficient manner even though the water discharged from faucet 21 falls freely through space before entering intake 26.

It will now be apparent that by the present invention I have provided a novel and efficient mixer for use with suction cleaners which need not be manually connected to the tap or faucet of a sink or basin; which is of simple construction and cheap to manufacture; which completely mixes the entrained dust and dirt with water and then discharges the same to drain; which is readily dismounted for cleaning; and in which there is no leaking and splashing of water around the joints thereof or from the discharge orifices therein.

Changes to or modifications of the above described illustrative embodiment of my invention may now be suggested to those skilled in the art without departing from my inventive concept. To determine the scope of this invention reference should be had to the appended claims.

What is claimed is:

1. In a water and dust mixer for suction clean-

ers, a water receiving receptacle, a water inlet adjacent the upper edge of said receptacle, air and water ports in said receptacle adjacent the upper edge thereof, a vessel nested in said receptacle and spaced internally therefrom, a perforated bottom for said vessel, a tubular member extending from said bottom and terminating short of the bottom of said receptacle, a filter housing received in the upper end of said vessel, a ring shaped gasket received in the lower end of said housing and bearing upon the upper end of said vessel, a spider in said housing resting on said gasket, a tubular filter resting on said spider and spaced from the walls of said housing and an air and dust inlet in the upper end of said housing discharging into said filter.

2. A mixer as described in claim 1 including a baffle extending downwardly and inwardly in said receptacle over said water inlet.

3. A mixer as described in claim 1 including downwardly depending handles for said receptacle disposed above and adjacent to said vents to deflect air and water downwardly from said vents.

4. A mixer as described in claim 1 including a downwardly and inwardly directed deflecting surface on the lower side of said gasket.

5. A mixer as described in claim 1 in which the upper edge of said filter is firmly but removably received in a circular groove in the top of said housing.

6. In a mixer, a receptacle having an open upper end, a vessel nested in said receptacle and spaced from the walls thereof and having a perforated bottom and an open top, a discharge opening in the bottom of said vessel, a filter housing mounted in the open end of said vessel,

a cylindrical filter mounted in said housing and spaced from the walls thereof, means for locking said receptacle, said vessel and said housing together to form air-tight seals therebetween, an air and dust inlet in said housing discharging into said filter, a water inlet adjacent the top of said receptacle and air and water ports in said receptacle adjacent the top thereof.

7. A mixer as described in claim 6 in which said water inlet includes a lip extending outwardly from said receptacle to receive and direct water into said inlet.

8. A mixer as described in claim 6 including a baffle extending downwardly and inwardly from said receptacle over said water inlet.

9. A mixer as described in claim 6 in which baffles extend downwardly and outwardly from said receptacle over said vents and provide lifting means for the mixer.

10. A mixer as described in claim 6 including a groove in the top of said housing to firmly but removably receive said filter.
